W^m A Greene.

UNITED STATES PATENT OFFICE.

W. A. GREENE, OF TROY, NEW YORK.

IMPROVED BLACKING-BRUSH.

Specification forming part of Letters Patent No. 42,655, dated May 10, 1864.

To all whom it may concern:

Be it known that I, WM. A. GREENE, of the city of Troy, county of Rensselaer, and State of New York, have invented or produced a new and useful Improvement in Blacking-Brushes; and I do hereby declare that the following is a full and exact description of the same, reference being had to the annexed drawings, and to letters of reference marked thereon, forming part of this specification, in which—

Figure 1 is a plan view of the blacking-brush stock. Fig. 2 is a longitudinal section of the same with the box. Fig. 3 is a perspective view of the same and Fig. 4 is a perspective view of the same as it appears when closed, the same letters referring to like parts in each of the figures.

My invention consists in constructing a blacking-brush in two sections, joining the same by a hinge, and in providing the back sides of said sections respectively with a cavity for the purpose of inclosing the blacking-box within said cavities when the brush is folded, substantially in the manner as now described and shown, viz: The stocks *a a* of the blacking brush are made of wood, and the brushes are secured to said stocks in the ordinary way, well known to brush-makers. The back side of each of said stocks is provided with a cavity, as shown in the annexed drawings, of sufficient diameter and depth to receive one-half or nearly one-half the thickness of the

blacking-box *B*. The said stocks are then joined to each other by means of a hinge, *K*, as shown in Fig. 1, thereby enabling the brushes to be folded upon and inclose within said cavity the blacking-box *B*, in the manner as shown in Fig. 4, or opened for use as shown in Fig. 3, thereby obtaining a compact, useful, and convenient article for the use of travelers, or for household purposes, the size of the brushes being governed by the size of the box used.

To pack the brush for transportation, place the blacking box within the cavity of the brush-stock, and fold the other stock upon it, thereby inclosing the blacking-box *B* in the cavities, in the manner as shown in Fig. 4, so as to occupy but a small space in trunks or bags. When wanting to use the same for blacking purposes, open the brushes, remove the blacking-box *B*, and perform the operation in the usual manner.

Having described my invention, what I claim as new therein, and desire to secure by Letters Patent, is—

The hinged blacking-brushes *a a*, when constructed so as to inclose a blacking box, in the manner substantially as herein fully shown, and for the purposes as described.

WM. A. GREENE.
